PLANT BALLING DEVICE

Robert S. Malkin, 257 Park Ave. S.,
New York, N.Y. 10010

Filed May 16, 1974, Ser. No. 470,627

Term of patent 14 years

Int. Cl. D15—03; D15—90
U.S. Cl. D35—1

FIG.1

FIG. 2

FIG. 3

FIG. 1 is a bottom plan view of a plant balling device showing my new design;

FIG. 2 is a side elevational view of the device of FIG. 1, the opposite side being substantially identical.

FIG. 3 is a top plan view of the device of FIG. 1.

I claim:

The ornamental design for a plant balling device, substantially as shown and described.
